[57] CLAIM

The ornamental design for a charger base for hand held battery operated vacuum cleaner, as shown and described.

DESCRIPTION

FIG. 1 is a front elevational view of charger base for hand held battery operated vacuum cleaner showing my new design, the left-side being a mirror-image view thereof;

FIG. 2 is a rear elevational view thereof;

FIG. 3 is a top plan view thereof;

FIG. 4 is a bottom plan view thereof;

FIG. 5 is a left-side elevational view thereof, the right-side being a mirror image thereof; and

FIG. 6 is a top, front and side perspective view thereof.

FIG. 1

FIG. 2

FIG. 3

FIG. 4

FIG. 5

FIG. 6
